JOSEPH G. SESSLER, OF CHICAGO, ILLINOIS, ASSIGNOR OF ONE-HALF TO FRED WILKEN,
OF CHICAGO, ILLINOIS

FIGURE WHEELED TOY

Application filed August 13, 1926. Serial No. 129,035.

My invention relates to toys and particularly to toys comprising apparatus whereby they may be propelled along rails or other suitable supports.

5 An object of the invention is to provide an improved toy of the kind described having objects or figures thereon to which relative motion is imparted by the propelling apparatus.

10 Many other objects of the construction herein shown and described will be obvious to those skilled in the art from the disclosure herein given.

To this end my invention consists in the 15 novel construction, arrangement and combination of parts herein shown and described, and more particularly pointed out in the claims.

In the drawings, wherein like reference 20 characters indicate like or corresponding parts:

Fig. 1 is a longitudinal vertical section taken through a toy embodying the invention;

25 Fig. 2 is a top plan view of the improved toy;

Fig. 3 is a bottom plan view of the improved toy;

30 Fig. 4 is an end elevation of the improved toy;

Fig. 5 is a fragmentary longitudinal central section taken through a toy embodying another form of the invention;

35 Fig. 6 is a fragmentary bottom plan view of the toy shown in Fig. 5; and

Fig. 7 is a fragmentary longitudinal section taken through a toy embodying still another form of the invention.

Referring for the present to Figs. 1 to 4, 40 inclusive, of the drawings, I have shown a preferred form of the invention embodied in a toy adapted to be used in connection with toy railways of the type that comprise third rails. The rails upon which the toy is adapted to travel are designated by the reference character 10, the third rail being shown at 11. In this instance, the third rail 11 is disposed intermediate the rails 10 but it will become apparent as this description progresses that any suitable arrangement of

rails may be employed without departing from the spirit of the invention.

The improved toy is preferably a miniature representation of a hand-car of the type commonly employed by section hands to travel 55 from point to point upon a railway and preferably comprises a truck 14 provided with wheels 15 and 16 arranged to travel upon the rails 10, the wheels 15 and 16 being mounted upon axles 17 and 18, respectively. 60 The truck 14 may be made of any suitable material, but I prefer to construct it from sheet metal, as indicated in the drawings. It preferably comprises a platform 19 adapted to support two or more figures 20 and 21 65 which represent workmen. The figures 20 and 21 preferably comprise feet members 23 secured to the platform 19. Pivots secured to the feet members 23 are leg members 24 which are, in turn, pivotally secured 70 to body members 25 having integral arm members 26. The arm members 26 are preferably secured to the opposite ends of a cross bar or lever 30 which is secured to a shaft 31 pivotally mounted in a bracket 75 member 33 mounted upon the upper side of the platform 19, the construction being such that when the lever 30 is oscillated the figures 20 and 21 will have such motion imparted to them that they will appear to be driving 80 the hand-car.

Secured to the shaft 31 is a lever 35 which is connected by a link 37 to a gear 38, the link 37 being pivotally secured to the gear 38 by a screw 39, or the equivalent, for the purpose. 85 It will be noted that the screw 39 is disposed eccentrically with respect to the axis of rotation of the gear 38 so that when the gear is rotated the lever 30 will be oscillated. The gear 38 meshes with a pinion 40 mounted upon the shaft 41 of a miniature electrical motor 42 mounted on a plate 43 which is rigidly secured to the truck 14. It will be noted that the bracket member 33 functions 90 substantially as a housing and partially encloses the motor 42 and other movable parts of the apparatus.

95 Fixed to the axle 18 is a gear 44 which meshes with the gear 38 and is adapted to 100

drive the axle when the motor 42 is functionally operative.

The means for delivering electrical energy to the motor 42 preferably comprises a brush or metallic roller 47 rotatably journaled in a track 48 carried at the free end of a leaf spring 50 which is secured to the platform 19 by a binding post 52. An electrical conductor 53 extends from the binding post to the motor 42. It is readily understood, of course, that electrical energy may be delivered to the third rail 11 from a suitable battery (not shown), or the equivalent, for the purpose and that this current may flow through the roller 47, the leaf spring 50, the binding post 52 and the electrical conductor 53 to the motor 42 to cause it to become functionally operative. As it is usual in toys of this character, one side of the motor 42 is grounded so that the current may return to the battery (not shown) through the axles and wheels of the toy which contact the rails 10, the rails 10 being electrically connected to one side of the battery (not shown).

Generally, I prefer to provide a gong or bell 56 arranged to be struck by a clapper 57 secured to the free end of a resilient rod 58 which projects from a lever 60. The lever 60 is pivoted upon a pin 61 mounted in the truck 14 and one end of the lever is connected by a link 63 to the aforementioned lever 35. When the motor 42 is functionally operative, the shaft 31 is oscillated and this motion is imparted to the clapper 57 through the link 63 and the lever 60.

The operation of the above described toy is substantially as follows: Means including a switch (not shown) is usually provided for operatively connecting the battery (not shown) to the third rail 11. When the switch is closed, the motor 42 becomes functionally operative and the axle 18 is rotated through the medium of the pinion 40 and the gears 38 and 44. Obviously, when the axle 18 is rotated, the wheels 16 will propel the toy along the track, the figures 20 and 21 being given the above described movements through the medium of the link 37 and the lever 35 which connect the gear 38 to the shaft 31. As the toy moves along the track, the clapper 57 will repeatedly strike the bell 56.

Referring to Figs. 5 and 6 wherein I have shown another embodiment of the invention, the reference character 14^a designates a truck which is preferably substantially identical with the aforementioned truck 14. The truck 14^a is provided with wheels 15^a and 16^a mounted upon axles 17^a and 18^a. As indicated in Fig. 5, the wheels 15^a and 16^a may be designed to travel along the rails 10. Secured to the axle 18^a is a gear 70 which meshes with a pinion 71 fixed to a shaft 72 journaled in a pair of plates 73 depending

from the truck 14^a. Also secured to the shaft 72 is a relatively heavy wheel or weight 74 in which a relatively large amount of energy may be stored to propel the toy along the tracks 10. The gear 70 meshes with a gear 38^a rotatably journaled on a stud shaft 75 and a link 37^a is preferably connected to the gear 38^a by a screw 39^a. The link 37^a is preferably employed to impart motion to figures 20^a and 21^a which are substantially identical with the aforementioned figures 20 and 21. The truck is preferably provided with a bell 56^a which may be operated by apparatus substantially identical with the apparatus provided for operating the bell 56 shown in Fig. 1.

The operation of the toy shown in Fig. 5 and 6 is substantially as follows: When it is desired to have the toy travel along the tracks 10, the toy is preferably set down upon a floor or any other suitable support and propelled along the floor or support a few times so that the wheels 16^a will rotate and impart this motion to the weight 74 through the gear 70 and pinion 71. After sufficient energy has been stored in the weight 74 the toy is quickly placed upon the tracks 10 whereupon the weight 74 continues to revolve for an appreciable period of time and causes the wheels 16^a to drive the toy along the tracks. Of course, the toy may be propelled along the floor by the weight 74, if it is so desired. When the toy is so propelled along the tracks 10, motion will be imparted to the figures 20^a and 21^a through the gear 38^a and the link 37^a.

In Fig. 7 I have shown still another form of the invention embodied in a toy which comprises a truck 14^b which is substantially identical in construction with the aforementioned trucks 14 and 14^a. The truck 14^b is provided with wheels 15^b and 16^b adapted to travel upon the tracks 10. The wheels 16^b are secured to an axle 18^b which is operatively connected to clock mechanism, the clock mechanism being designated generally by the reference character 80. Any suitable clock mechanism may be employed but I preferably provide a main spring (not shown) which is operatively connected through an escapement (not shown) to the axle 18^b. The main spring (not shown) may be tensioned by rotating a shaft 81 which is engageable by a suitable key (not shown).

Secured to the axle 18^b is a gear 82 which meshes with a gear 38^b rotatably mounted upon a stud shaft 84 mounted in the truck 14^b. A link 37^b pivotally connected to the gear 38^b is adapted to impart motion to figures 20^b and 21^b through apparatus (not shown) which is substantially identical with the apparatus employed to impart motion to the figures 20 and 21 of Fig. 1.

The operation of the toy shown in Fig. 7

is substantially as follows: When it is desired to have the toy travel along the tracks 10, the main spring (not shown) of the clock mechanism 80 is tensioned by rotating the 5 shaft 81, the aforementioned key (not shown) being employed for this purpose. The toy is then placed upon the rails 10 and the clock mechanism drives the wheels 16^b which, in turn, drives the toy along the tracks.

10 Having thus described my invention, it is obvious that various immaterial modifications may be made in the same without departing from the spirit of my invention; hence I do not wish to be understood as limiting myself to the exact form, construction, 15 arrangement and combination of parts herein shown and described or uses mentioned.

What I claim as new and desire to secure by Letters Patent is:

20 1. A toy of the class described including a truck, wheels for said truck, axles between said wheels, a gear fixed to one of the axles between said wheels, a supporting plate upon the truck, a motor carried by the supporting plate, a pinion carried by the motor shaft, a gear forming connection between the pinion and the gear on one of the axles for propelling the truck, a bracket supported upon the truck and housing the plate, a transverse 25 shaft supported by the bracket, a lever pivoted upon the shaft, articulated figures upon the truck, each having pivotal connection with one end of the lever, and a link having one end eccentrically connected to the second- 30 mentioned gear and the other end operatively connected to the shaft for imparting a rocking movement to the lever whereby to simultaneously actuate said figures with the movement of the wheels.

40 2. In a toy of the class described and in combination a truck, wheels for said truck, axles between said wheels, a gear fixed to one of the axles between said wheels, a supporting plate upon the truck, a motor carried by the supporting plate, a pinion carried by the motor shaft, a gear forming connection between the pinion and the gear on one of the axles for propelling the truck, a bracket supported upon the truck and housing the 45 plate, a transverse shaft supported by the bracket, a rocker lever pivoted upon the shaft, articulated figures upon the truck and each having a pivotal connection with one end of the rocker lever, a sound device disposed on the underside of the plate, a pivotal clapper lever adjacent the sound device on the said plate, a link connecting the rocker lever and clapper lever, another link having one end 50 eccentrically connected to the second mentioned gear, and the other end operatively connected to the shaft for imparting a rocking movement to the lever and to the link connecting the clapper lever, to simultaneously actuate the articulated figures and the 55 60 65

sounding device when the wheels of the truck are in motion.

In testimony whereof, I have hereunto signed my name.

JOSEPH G. SESSLER.
